UNITED STATES PATENT OFFICE.

JOHN E. MITCHELL AND DENNIS PARKS, OF ST. LOUIS, MISSOURI.

HULL-BOARD CONSTRUCTION.

1,332,913.

Specification of Letters Patent.

Patented Mar. 9, 1920.

Application filed March 15, 1919. Serial No. 282,910.

To all whom it may concern:

Be it known that we, JOHN E. MITCHELL and DENNIS PARKS, citizens of the United States, residing in the city of St. Louis and 5 State of Missouri, have invented new and useful Improvements in Hull-Board Construction, of which the following is a specification.

This invention relates to a boll breaking 10 and cotton separating machine, and has for its general object an improved construction of hull board designed in operation to facilitate the process of separating the cotton from the bolls and hulls and to prevent congestion in the working chamber of the machine. The invention also has for its object to provide means for separately delivering the waste, consisting of hulls and trash, and the unopened bolls and wads of cotton, 15 passing from the working chamber so that the latter may be subjected to further treatment to secure the recovery of substantially all of the available cotton from the product fed into the machine.

20 The difficulty of adjusting the lower edge of the hull board sufficiently close to the saw cylinder to prevent cotton passing through with the hulls and trash without, at the same time, causing a congestion in the working 25 chamber by reason of large hull particles and unopened bolls being unable to escape from the chamber, has been pointed out by us in prior cases. To overcome this objection, the double hull board construction described and 30 claimed in Patent No. 1,030,913, dated July 2, 1912 was devised by one of the present inventors, John E. Mitchell.

The present invention illustrates another 35 means of accomplishing such purpose while 40 at the same time enabling the use of a simpler construction of machine, in that only a single hull board is employed. The present machine also permits the recovery of a very high percentage of cotton, in that provision 45 is made for insuring the separation of the hulls and trash, and any unopened bolls and cotton passing from the machine, so that the latter, as stated, may be subjected to further treatment.

50 The invention is illustrated in the accompanying drawings in which:

Figure 1 is a cross sectional view of the machine constructed according to our invention; and

55 Fig. 2 is a broken view in rear elevation

of the hull board and parts immediately associated therewith.

Referring now to the drawings, the numeral 1 indicates, generally, the frame of the machine, the upper portion 2 of which provides a hopper in which are rotatably mounted feed rolls 3. Below the rolls 3 is rotatably mounted a boll breaking cylinder 4, which is partially inclosed by means of a casing member 5 and a screen 6, a throat, or 60 passage, 7, being provided at the bottom of the chamber formed by the members 5 and 6 for the escape from the boll breaking chamber of the mixed cotton and hulls produced by the action of the breaking cylinder 4 on 70 the bolls thrown into the hopper.

Rotatably mounted in the casing below the boll-breaking chamber is a saw cylinder 8, a kicker roll 9, and a doffer roll 10, the construction and operation of which are well 75 known, and need not be particularly described. The passage 7 from the boll-breaking chamber communicates with a working chamber 11, where the mixed cotton, hulls and trash are received for the purpose of 80 being separated, the cotton being drawn through by the saw cylinder and removed by the doffer roll, and unopened bolls, and hulls and trash being knocked back by the kicker roll. Coöperating with the saw cylinder 8, 85 is a hull board 11, which extends below the screen 6, its lower edge 12 being positioned sufficiently close to the saw cylinder to prevent the escape of cotton through the space 13 provided, while permitting the escape of 90 the greater portion of the hull particles and trash. As frequently happens, however, a certain number of unopened bolls will pass into the working chamber, having failed to

be broken up by the breaking cylinder 4, 95 and these are too large to pass through the space 13 between the lower edge of the hull board and the saw cylinder. Also some of the hulls will not be broken apart, and the size of these bodies is such as to prevent them 100 from passing through the passage 13. Such unbroken bolls, unseparated hulls, and pieces of trash, would ordinarily, with the use of a single hull board, adjusted as described, collect in the working chamber and sooner 105 or later cause the same to be congested. To obviate this result, we provide one or more larger openings between the hull board and saw cylinder to permit of the discharge of such unbroken bolls, unseparated hulls, or 110

other large bodies which cannot escape from the machine through the regular space 13, between the bottom of the hull board and the saw cylinder. Such larger opening, or 5 openings, are provided by cutting one or more recesses 14 in the lower edge of the hull board, which open into the passage 12, and provide sufficiently large spaces for the passage through them of the larger bodies referred to. The drawings show three of such 10 recesses, but a greater or less number may be employed. In order to separate the hulls and trash passing through the space 13, from the larger particles, unbroken bolls, and 15 wads of cotton which may fall through the larger spaces provided by the recesses 14, we secure in each recess 14 the upper end of a chute 15, the lower end of which opens into a chamber 16 in the bottom of which is a 20 conveyer 17, and arrange the passage 13 to communicate with a chamber 18, in the bottom of which is a conveyer 19, the chambers 16 and 18 being separated by a partition 20. The chutes 15 pass through an upper inclined portion of the partition, as shown. 25 The chutes 15 have side walls 15^a, and the upper ends of these chutes entirely inclose the recesses 14, so that the product passing through these recesses is maintained separate from the product passing through the space 13.

In the operation of the machine, the cotton will be caught up by the saw cylinder 8, and trash and all hulls which have been 30 broken apart, or separated from each other, will escape through the passage 13 into the chamber 18. Any unbroken bolls in the working chamber above the saw cylinder are moved around, or back and forth, by the 35 operation of the saw cylinder very rapidly within the working chamber, and, therefore, soon fall, or escape, through the openings 14 in the bottom of the hull board and are discharged by the chutes 13 into the chamber 40 16. This will occur to a greater or less extent even with a single opening, and in practice, therefore, it has not been found necessary to provide very many of the openings 14, three of such openings being usually 45 sufficient. The width of the recesses 14 may vary, but ordinarily five inches would be the maximum width.

It will be obvious that the bottom edge of the hull board 11 can be set so as to permit 50 a free discharge of hulls through the space 13 without permitting the escape of any cotton of value with the same into the chamber 18, whereas an occasional lock, or wad, of cotton may fall through the larger spaces 55 provided by the recesses 14 with the unbroken bolls into the chamber 16. The hulls comparatively free from cotton in chamber 18 are discharged by the conveyer 19 to the hull pile, while the unbroken bolls and the 60 small amount of cotton passing into the

chamber 16, are carried out of the machine by the conveyer 17, and either conducted to a separate re-cleaner, or returned with the bulk of cotton going to the main battery of the machine.

70

We claim:—

1. A boll breaking and cotton separating machine affording a working chamber, a saw cylinder operating in said chamber, a hull board coöperating with said saw cylinder and providing different sizes of openings past the same for the escape of waste and other products from the working chamber, and means for separately delivering the products passing through the different openings.

75

2. A boll breaking and cotton separating machine affording a working chamber, a saw cylinder operating in said chamber, a hull board coöperating with said saw cylinder having its lower edge defining the size of a passage past said saw cylinder and provided with a recess affording an enlarged opening past said saw cylinder, said passage and opening affording means of escape for waste and other products from said working chamber, and a chute leading from said recess, whereby to separately deliver the products passing through said recess from the products passing through the smaller space provided by the remainder of the bottom edge of the hull board.

90

3. A boll breaking and cotton separating machine affording a working chamber, a saw cylinder operating in said working chamber, a hull board coöperating with said saw cylinder having its lower edge portion defining the size of a passage past said saw cylinder and provided with a plurality of recesses affording enlarged openings past the saw cylinder, said passage and openings affording means of escape for waste and other products from said working chamber, a chute secured about each one of said recesses for conducting away the products passing through such enlarged openings, and means for maintaining separate such products from those passing through the passage provided by the remainder of the hull board.

100

4. A boll breaking and cotton separating machine having a casing providing in its bottom two separated compartments and affording a working chamber, a saw cylinder operating in said chamber, a hull board coöperating with the saw cylinder and having its lower edge portion defining the size of a passage past said saw cylinder communicating with one of said compartments, said passage affording means of escape for waste from the working chamber, and said hull board being provided in its lower edge portion with a recess affording an enlarged opening past the saw cylinder for the escape of relatively large bodies from the working

115

- chamber, and a chute leading from said recess to the other compartment.
5. A boll breaking and cotton separating machine comprising a casing affording a working chamber and having in its bottom two conveyers separated by a partition, a saw cylinder operating in said chamber, a hull-board coöperating with said saw cylinder, and having its lower edge defining the size of a passage past said saw cylinder communicating with one of said conveyers, said passage affording means of escape for waste from said chamber, and said hull
- board being provided in its lower edge portion with a recess affording an enlarged opening past said saw cylinder for the escape of relatively large bodies from said working chamber, and a chute having its upper end inclosing the bottom of said recess and its lower end extending through said partition and communicating with the other conveyer.
- 10 In testimony whereof, we have hereunto set our hands.

JOHN E. MITCHELL.
DENNIS PARKS.
